UNITED STATES PATENT OFFICE.

THOMAS R. WEYANT, OF NEW YORK, N. Y.

WINDOW VENTILATOR.

Application filed April 14, 1921. Serial No. 461,197.

This invention relates to window ventilators of the type wherein a deflector is located upon the window sill, at the inner side of the room, opposite to the lower window sash, and the latter is partially opened; whereby the air enters and strikes the deflector, which directs it upwardly, and the incoming current is in this manner spread over the entire room gradually and evenly, and also uniformly, without causing any draft which is injurious to the occupants.

The principal object of my invention is to provide an improved ventilator of this type, which is simple, inexpensive, conveniently and economically manufacturable, convenient and economical of installation by the user without requiring any skill, conveniently utilizable, strong, rigid and durable, and which when in use may be readily and conveniently detached entirely from its place by the user, and reattached by him when it is desired to return it to its operative position.

Another object of the invention is to provide a ventilator of this type, which is entirely manufacturable and capable of being fitted to any width of window, without requiring any special work or any kind of reconstruction of any part thereof.

Other objects and advantages will herein-after appear.

In the accompanying drawings,—

Fig. 1 is a vertical section of the ventilator, showing it in installed operative state.

Fig. 2 is a plan view of the ventilator, shown in Fig. 1, the same being shown as partially broken away.

Fig. 3 shows a detail of the ventilator.

Fig. 4 is a front elevation of the ventilator shown in Fig. 1.

Figs. 5, 6, 7, 8 and 9 show details of the ventilator.

Upon the sill 1 is positioned a deflector 2 which is adapted to swing, in the manner hereinafter described, toward and away from the lower sash 3 of the window 4. To each side of the window-frame 5 is secured a fitting 6 by means of wood-screws 7, and to each fitting is joined a section 8 of a side-bracket 9, which brackets carry the deflector 2. The fitting 6 is provided with a pair of stamped out flanges 10, Figs. 5, 6, 7, that comprise central circular portions 11 with elongated bars 12 extending therefrom in opposite directions, and each section 8 is provided with a pair of openings 13 that are

of a similar configuration and slightly larger in area. When it is desired to join the section 8 to the fitting 6, it simply requires insertion of the flanges 10 of the fitting into the openings 13 of the section 8 and dropping the latter downwardly, whereupon the circular portions 11 of flanges 10 pass through the openings 13 of sections 8 and become positioned behind the narrow parts 65 of said openings and in this manner lock the sections 8 securely to the fittings 6. To the corner 14 of each section 8 is pivoted a pair of triangular sections 15, 16 forming part of the bracket 9, and the deflector 2 70 is directly joined to the section 16. The corners of the bracket-section 15, are provided with projections 18 which are bent over the upper rims of sections 8, 16, in the manner shown, whereby those projections 75 abut against extensions 17 formed at the corners of the sections 8, 16 and in this manner hold the sections to each other, guide the sections 15, 16 when they are

swung about their pivot 14 and limit the 80 swinging movement of sections 15, 16 about their pivot 14. The brackets 9 thus consist of the sections 8, 15, 16 which spread out or open up in fan-like manner about their common pivot 14, and which may be 85 folded up or closed until the three sections overlap each other, and as these sections are opened and closed the deflector 2, which is joined to the section 16, is thereby similarly 90 swung about the pivot 14, toward and away from the lower window-sash 3, from the inclined position shown to a vertical position and backwardly. Said deflector comprises a pair of angular frames 19, which telescope each other, Fig. 3, and between which is 95 mounted a glass pane 20 that is held in place laterally by means of bolts 21 which pass through said frames to secure them to each other, together with the pane 20. The bolts 21 are tightened by means of nuts 22 which 100 thread thereover and are provided with enlarged heads 23 and shanks 24 of reduced diameter. The bracket sections 16 are provided with bent portions or rails 25 having key-hole shaped openings 26, each comprising a circular part 27 and a narrow elongated part 28. When it is desired to mount the deflector 2 in operative place, it merely requires passing the heads 23 of nuts 22 through the circular parts 27 of the openings 105 26, and then sufficiently lowering the deflector to permit the shanks 24 to pass

through the parts 28 of said openings, with the heads 23 of the nuts positioned behind the rails 25, as shown in Figs. 1, 2. A link 29 is pivoted at 30 to the bracket-section 16, a similar link 31 is pivoted at 32 to the section 8, and a thumb-screw 33 passes through the extremity of link 29 and threads into the extremity of link 31, whereby loosening of the thumb-screw 33 permits free pivoting of the links about the shank of said screw, while tightening of the thumb-screw locks the two links to each other, and in this manner the deflector 2 may be locked in any desired position. Thus, the deflector may be swung and set to an extreme inclined or open position, to admit a maximum of air and ventilation, or it may be set to a vertical or extreme closed position for minimum ventilation in stormy or cold weather, or it may be set to any intermediate inclined position, as shown, and upon tightening of the thumb-screw 33 the deflector may be locked in any position to which it has been set. Adjacent to the window sash 3 is located a screen 34 which rests upon the sill 1 and serves to prevent entering of dust, insects, etc., into the room during the ventilation. The fitting 6 is provided with a bent L-shaped tongue 35, and the frame 36 of said screen is provided with a channelled groove 37, and in order to mount the screen in proper position it merely requires lowering of the same in such manner that the tongue 35 of fitting 6 passes through the groove 37 of the screen, as shown in Fig. 2.

All that is required to install the ventilator, therefore, is to secure the fitting 6 in place by its screws 7, then placing the brackets 9 in position by means of interlocking its openings 13 with the flanges 11 of the fittings, and then mounting the deflector 2 in position by means of interlocking its nuts 22 with the openings 26 of the rail 25 of bracket-section 16, and these operations can be easily executed personally by any purchaser of this ventilator without requiring skill or any help. It will be also evident that to temporarily remove the ventilator, during warm weather or for window repairs, all that is necessary is demounting the deflector 2 by merely lifting it slightly and withdrawing it from the bracket rail 25, then removing the brackets 9 by simply lifting each of them slightly and withdrawing it from the fitting 6, and then the screen 34 may be removed by elevating it upwardly and thereby disengaging it completely from the fitting 6. When it is desired to replace the ventilator the same is easily performed by repeating these operations in an opposite order and manner.

In the manufacture of this ventilator, the deflectors 2 and screens 34 are made of lengths so as to fit the ventilator to windows the widths of which are 20", 25", 30", 35",

etc., as these are the most common dimensions for window widths. Should it be necessary, however, to fit the ventilator to a window of special width, such as 29 inches, the same can be accomplished by a pair of fillers 38 and 39, Figs. 8, 9. Each of the fillers 38 is provided with a button 40, which button 40 interlocks with the openings 26 of the bracket-rails 25, and the filler is also provided with openings 41, similar to the openings 26, which openings 41 interlock with the nuts 22 of the deflector 2. Each of the fillers 39 is provided with a stamped-out portion 42 which interlocks with openings 43 in the fittings 6, that are similar to the key-hole shaped opening 26, and the filler is provided with an L-shaped extremity 44 adapted to pass through the groove 37 of the screen. In order to install the ventilator upon a window of this odd size, therefore, it is only necessary to select pairs of 2 inch fillers and interlock these fillers 38, 39, with the rails 25 and fittings 6, and then the regular deflector and screen adapted to fit a 25 inch window may be mounted in the usual manner by interlocking them with the said fillers. Should the width of the window be a fraction of an inch over 29 inches, such as 29½ inches, this condition can be remedied by inserting a ¼ inch piece of wood between each fitting 6 and the window-frame 5, and then screwing the fitting 6 in place. Fillers of various widths are thus supplied to provide for all windows of various widths. If it is desired to equip a window of unusual width, of about 60 inches and upwards, it is preferable to utilize two deflectors and two screens, that are adapted for 30 inch windows, instead of using one special long deflector and one long screen for such special purpose. In such case the two deflectors and two screens may be placed end to end, as shown in Figs. 8, 9, straps 45, 46 may be placed at each side of the joining extremities of the deflectors, and screws 47 may be then passed through the straps 45, Fig. 8 and through the openings 48 intended for the bolts 21 and the screws may be threaded into the straps 46. In a similar manner screws 47 may be passed through the straps 45, Fig. 9, and openings 49 in the screen and threaded into the straps 46.

It will be evident that this ventilator and every part thereof is entirely manufac-turable and that no special work is necessary for equipping any window of any size, by which is meant that when an order is received for a ventilator for a window of any width, all of the parts constituting the ventilator for such window may be thereupon supplied for immediate installation, without requiring any special construction or alteration whatever of the ventilator or any part thereof.

Variations may be resorted to within the 130

scope of the invention, and portions of the improvements may be used without others.

Having thus described my invention, I claim:—

- 4 1. A window ventilator having the combination with side brackets, and a deflector, of means for joining the deflector to said brackets including headed bolts, said brackets having slots adapted to receive said 10 bolts and permit them to drop downwardly therethrough for mounting the deflector upon the bracket, said deflector comprising a pair of frames, a pane of glass fitted between said frames, and said bolts passing through 15 said frames and securing them to each other.

2. A window ventilator having the combination of a fitting adapted to be permanently secured to the window, a side bracket, a deflector, means to join said deflector to said bracket, means to attach said bracket to and 20 detach it from said fitting, said bracket having a guide, a screen, and said screen having a recess adapted to slide over said guide and receive the guide for joining the screen to said fitting. 25

Signed at the city of New York, in the county of New York, and State of New York, this 8th day of April, A. D. 1921.

THOMAS R. WEYANT.
